UNITED STATES PATENT OFFICE.

JOHN HUGHES, OF BUCHANAN, PENNSYLVANIA.

Letters Patent No. 93,535, dated August 10, 1869.

IMPROVEMENT IN LANTERNS.

The schedule referred to in these Letters Patent and making part of the same.

To all whom it may concern:

Be it known that I, JOHN HUGHES, of Buchanan, in the county of Allegheny, and State of Pennsylvania, have invented a new and useful Improvement in Guard-Lanterns; and I do hereby declare that the following is a full, clear, and exact description thereof, reference being had to the accompanying drawings, making part of this specification, in which—

Figure 1 is a diametrical section through a lantern having my improvement applied to it.

Figure 2 is a perspective view, illustrating more clearly my improvement.

Similar letters of reference indicate corresponding parts in the two figures.

The object of my invention is to improve portable lanterns, which are adapted for receiving and holding in place removable globes, by making a part of the base-ring of the guard-frame as the pintle of the hinge-connection of this frame to the base of the lantern. Also, by adapting a catch, to hold the base and guard-frame in proper position, by arranging such catch so that it will receive and hold beneath it the base-ring of said frame, thereby producing a removable globe-lantern at much less cost of labor and material than hitherto, as will be hereinafter explained.

To enable others skilled in the art to understand my invention, I will describe its construction and operation.

In the accompanying drawings—

A represents the removable globe of the lantern, which is constructed with circular contracted portions, and annular external ribs g g', upon its extremities.

B is the perforated top of the lantern, which has the upper ends of all the vertical wires E' of the guard-frame secured to it, by bending these ends inwardly and soldering them to the base-flange of this top or cap.

The lower ends of the vertical wires E' are secured to a base-ring, a, and at an intermediate point between the ring a and cap B, the strengthening-ring F is secured to wires E, thus completing the guard-frame.

The base-section C, of the lantern, which contains the removable lamp D, is constructed with an internal flange, e, near its bottom, for receiving the spring-supports and fastening d, on the lamp, as shown in fig. 1.

The upper end of this base-section is constructed with an external annular flange, e, which is corrugated, to stiffen it, and also to afford a depressed seat for the rib or bead at the upper terminus of the contracted portion g of the glass globe to rest in or upon.

To the circumference of this flange e the base-ring a of the guard-frame is connected by a strap, b, which is soldered or riveted to the flange, so as to form a hinge-connection of the guard-frame to the base of the lantern.

To hinge this ring properly to the flange e, it is necessary to bend the wire of the ring outwardly, and straighten that portion of it which is to form the pintle of the eye-piece b. This is shown clearly in fig. 2.

Diametrically opposite the hinge-connection a spring-strip, G, is secured to the base C, below flange e, and extended up and over this flange, so as to form a catch, with an outwardly-inclined finger-piece, G', which catch will receive beneath it the ring a, and firmly hold this ring and the flange e together, as shown in fig. 1.

It will be seen, from the above description, that the glass globe A is held in place between the cap B and base C, without cement, consequently it can be removed at pleasure, for cleaning it, or for substituting a good globe for a broken one; also, that the base-ring a of the guard-frame, serves as the pintle for the hinge-connection of this ring with the base C; also, that the base-ring a serves, in conjunction with a spring-catch, as a means for securing the hinged sections of the lantern in the condition represented in fig. 1.

These features, all combined in the manner shown and described, admit of lanterns being made strong and substantial, and at the same time their cost, as compared with lanterns hitherto made, is greatly diminished.

I am aware of the lanterns patented by John H. Irwin, September 11, 1866, and by Charles F. Moeller, August 14, 1866. I also am aware of the rejected application of George Pengeot, filed in 1866.

In all of these lanterns the spring-fastening is constructed and applied in a more costly and inconvenient way than in my lantern, and in the latter two, the globe cannot turn over to one side any further than the quarter of a circle, and hence there is great inconvenience in the handling of these lanterns when the globe is thrown over, it being necessary to employ both hands for the purpose.

In view of the great convenience of my external spring-catch, and the cheapness with which my lantern is constructed, I believe I have made a great improvement, although the general operation and design may be somewhat similar to the lanterns herein referred to.

What I claim as my invention, and desire to secure by Letters Patent, is—

1. The combination and arrangement of the external spring-catch G G', the hinge b, the base-ring a of the guard-frame, and the removable or loose globe A, the whole being constructed as described, and so operating, that by a pressure of the thumb upon the spring in an outward direction, the globe-guard will be uncaught from the oil-reservoir stand, and can be turned over on its hinge a full half circle, and the globe removed for cleaning, and then, by turning it back, the

outward pressure of the base-ring upon the spring-catch will force said catch out of the way, and said ring will fall below the hook of the catch, and be caught and retained thereby in a firm manner, all as set forth.

2. The combination of the base-ring *a*, which is straightened at the point where it is hinged to the flange *e*, with the said flange, which is constructed to

support said ring at all points, and also the portion *g* of the glass globe, and with the external spring-catch *G*, *G'*, all arranged, constructed, and operated in the manner herein described and shown.

JOHN HUGHES.
